UNITED STATES PATENT OFFICE.

WILLIAM T. BRADLEY, OF LINN, MISSOURI.

SHARPENING APPARATUS.

Application filed October 23, 1926. Serial No. 143,574.

This invention relates generally to an apparatus for sharpening cutting elements, and particularly to an apparatus adapted for use in sharpening the blades of knives and scissors, the predominant object of the invention being to produce an extremely simple and inexpensive means for sharpening the blades of the cutting elements mentioned in a manner to maintain proper bevels at the cutting edges thereof.

As is well known, it is absolutely essential in sharpening the blades of knives and scissors that the bevels at the cutting edges of said devices be properly maintained. In the use of sharpening apparatus heretofore employed, the proper maintenance of the bevels referred to depended largely on the skill of the operator, hence the inexperienced person using one of said sharpening apparatus frequently had considerable difficulty in successfully performing the sharpening operation.

The apparatus disclosed in the present application includes means whereby the position of the abrasive supporting element of the apparatus may be regulated, thus providing for the maintenance of the abrasive at a predetermined angle with respect to the blade being sharpened. In view of this arrangement, it is obvious that the proper angle will be formed at the cutting edge of the element being sharpened, regardless of the skill of the operator, inasmuch as it will be only necessary after the angle regulating means of the apparatus has been properly adjusted for the operator to move the abrasive across the cutting edge of the blade being sharpened.

Fig. 1 is a plan view of the blade holder of my improved apparatus.

Fig. 2 is an end elevation of the blade holder illustrated in Fig. 1.

Fig. 3 is a cross-section on line 3-3 of Fig. 1.

Fig. 4 is a plan view of the abrasive supporting element of my improved apparatus.

Fig. 5 is a side elevation of the abrasive supporting element illustrated in Fig. 4, a portion of the handle thereof being broken away to show the adjustable angle regulating means.

Fig. 6 is a plan view of the abrasive supporting element of my improved apparatus when a file is employed in the sharpening operation.

Fig. 7 is a view illustrating the manner

in which the blade holding element is clamped to a support, and showing a scissors as it will appear when held by the holding element during the sharpening operation.

Fig. 8 is an enlarged fragmentary section on line 8-8 of Fig. 7.

In the drawing A designates the blade holding element of my improved apparatus, and B the abrasive supporting element thereof. The blade holding element comprises a pair of spaced end walls 1 and 2, which are connected together at their lower portions by a bottom wall 3. 4 designates an angular member which is associated with the blade holding element A, said member 4 having a portion 4' which is parallel with and spaced apart downwardly from the bottom wall 3 of the holding element, as shown in Fig. 7. 5 designates a clamping device which includes a threaded shank 6 extended through a threaded opening in the portion 4' of the angular member 4, a head 7 movable with said threaded shank and a winged means 8 for rotating said threaded shank. When the holding element of my improved apparatus is in use, it is clamped to a table top, or other suitable support T in the manner illustrated in Fig. 7. That is to say, an edge portion of the table top is located between the bottom wall 3 and the portion 4' and the threaded shank 6 is rotated in a direction to cause the head 7 to be forced firmly against the bottom face of the table top.

Interposed between the end walls 1 and 2 is a pair of elongated pockets 9, said pockets each being extended from the wall 1 to the wall 2, and being slightly tapered in cross-section with the narrower portions at the outer ends thereof, as shown clearly in Fig. 95

3. Each of the pockets 9 comprises approximately parallel top and bottom walls 10 and 11, an end wall 12 and walls 13 which extend downwardly from the blade receiving portion of the pocket to the bottom wall 3. The function of the last mentioned walls being to add rigidity to the structure. If desired, the pockets 9 may be formed as integral parts of the blade holding element A, although this is not essential, as said pockets may be formed separately and be secured to the holding element in any suitable manner. As shown in Fig. 3, the blade receiving portions of the pockets 9 are inclined upwardly and said pockets are extended outwardly in opposite directions.

Formed in the end walls 1 and 2 of the

holding element A is a plurality of slots 14, said slots being each of approximately the same shape as the cross-sectional shape of the blade receiving portions on the pockets 9. That is to say, each slot is tapered so that its narrower portion is at the outer end thereof. The slots 14 are so located that the blade receiving portion of each individual pocket is in alignment with a slot in the wall 1 and a slot in the wall 2. In view of this arrangement, it is plain that a blade to be sharpened may be passed into the slots 14 and into the pockets 9, as shown in Fig. 2, in which view C designates a blade to be sharpened. It is plain, of course, that because the blade holder is relatively short when compared with the length of the blade of the average knife, said blade will project beyond the holding element at the opposite ends thereof, and it is also obvious that the blade may be moved longitudinally of the pockets 9 to present different portions thereof between the walls 1 and 2.

Extended outwardly from the wall 2 of the blade holding element of my improved apparatus at the lower portion thereof is a member 15, which is provided with an inclined face 16 having teeth 16' cut therein. The member 15, if desired, may be formed integral with the wall 2, or said member may be a separate element secured to said wall in any suitable manner. 17 designates a notch which is formed in the wall 2 at the upper edge thereof at a point immediately above the member 15, a wall of said notch being provided with a plurality of shoulders 18 for a purpose to be hereinafter set forth. 19 designates a plurality of teeth formed in the upper edge portion of the wall 1 at a point opposite to the notch 17.

The member 15, notch 17 and teeth 19 referred to are employed when a scissors is to be sharpened. In associating a scissors with the holding element A, so that it will be held thereby during the sharpening operation, one blade of the scissors is arranged in the notch 17, as shown in Figs. 7 and 8, in which position the back portion of the blade adjacent to the outer end thereof will contact with the teeth 19, whereby lateral movement of the outer portion of said blade is prevented. With one blade of the scissors in the position described, the other blade is moved to an approximately vertical position, as shown in Fig. 7, and the handle portion of said vertically arranged blade is moved inwardly toward the holding element in contact with the inclined face 16 of the member 15. This will have the effect of rotating the blade within the notch 17 axially, thereby forcing the blade of the scissors against the opposite walls of the notch 17, whereby said blade will be tightly gripped within said notch, and because of the presence of the teeth 16' on the inclined face 16

of the member 15, the chance for accidental movement of the vertically arranged blade of the scissors is greatly reduced.

Referring now to Figs. 4 and 5: 20 designates the handle portion of the abrasive supporting element of my improved apparatus. 21 designates a flat strip of material, one end of which is reduced in size and is introduced into an aperture formed in the handle 20, a suitable wedge 22, or similar device, being employed to cause said flat strip to be securely fixed to said handle. The flat strip 21 is provided with an offset portion 23, which is shaped to receive the abrasive 24 of the apparatus, said abrasive being interposed between an angularly arranged wall 24' of the flat strip 21, and an end of a clamping screw 25, which passes through a threaded opening in the down-turned portion 26 of the flat strip 21. It is obvious, in view of this arrangement, that abrasives of different sizes may be employed, and when a smaller abrasive is used, as suggested in Fig. 5, fillers 27 of any suitable material may be employed to cause the abrasive to assume its proper position.

Formed through the handle 20 of the abrasive supporting element B of my apparatus is a smooth opening, through which an adjustable member 28 is passed, said adjustable member comprising a threaded shank 29, having a head 30 at its lower end. 31 designates a locknut, which is adapted to contact with the lower portion of the handle 20, and 32 designates a wingnut which contacts with the handle 20 at the top thereof. It is plain that the shank 29 may be adjusted transversely of the handle 20 by simply manipulating the locknut 31 and the wingnut 32, said locknut and wingnut being adapted to firmly lock said shank in any position to which it may be adjusted.

When either the knife blade or the scissors which is to be sharpened has been gripped by the blade holding element A, as already described, the threaded shank 29 associated with the handle 20 of the abrasive supporting element B is adjusted so that when the head 30 of said shank rests upon the table top or other support T, to which the blade holding element is fixed, the bottom face of the abrasive will be parallel with the face of the bevel at the cutting edge of the element to be sharpened. The abrasive supporting element is then reciprocated with respect to the blade being sharpened with the head 30 passing back and forth always in light contact with the support T. The result of this will be that the bevel of the cutting edge of the blade will be maintained, for as long as the head 30 is moved along in contact with the support T the bottom face of the abrasive will be absolutely parallel with the bevel of the cutting edge being sharpened.

It has been stated heretofore that a wall of the notch 17 is provided with a plurality of shoulders 18. These shoulders are used when a scissors having a relatively narrow blade 5 is being sharpened. It is conceivable that a scissors blade may be so narrow that its cutting edge would not extend above the notch 17 when the back of the blade is in contact with the bottom of said notch. In the use 10 of my improved apparatus, however, the back of the narrow scissors blade instead of being in contact with the bottom of the notch 17 will rest upon one of the shoulders 18, which arrangement will bring the cutting 15 edge thereof above the top of the notch. A scissors blade which rests upon one of the shoulders 18, as described, will be gripped in place within the notch 17 in the same manner as if it were resting upon the bottom of the 20 notch.

Fig. 6 illustrates the abrasive supporting element of my improved apparatus when same has a file associated therewith instead of a stone, as in Fig. 5. When it is desired 25 to change from the arrangement shown in Fig. 5 to that shown in Fig. 6, the wedge 22 is removed and the flat strip 21 detached from the handle 20, after which the reduced end portion of the file 21' may be introduced 30 into the aperture in the handle 20', and a wedge 22' introduced in place to rigidly fix the file to the handle.

The blade holding element of my improved apparatus is provided with a pair of 35 pockets 9, which extend in opposite directions, as shown in Figs. 2 and 3. The reason for having more than one pocket is to permit of the sharpening operation being performed from opposite sides of the holding element, 40 and also to permit of a blade being reversed when it is desired to sharpen both sides of the cutting edge thereof.

I claim:

1. A device for holding cutting elements 45 to be sharpened comprising a member having spaced end walls, and an elongated pocket interposed between said spaced end walls, said end walls being provided with openings in alignment with said pocket, said 50 openings being of approximately the same shape as the cross-sectional shape of said pocket and said pocket and said openings being adapted to receive the blade of the cutting element to be sharpened.

55 2. A device for holding cutting elements to be sharpened comprising a member having spaced end walls, and a pair of upwardly inclined elongated pockets interposed between said spaced end walls, said pockets being 60 extended in opposite directions and being open along their outer edges, said end walls being provided with open end slots in alignment with said pockets, said openings being 65 of approximately the same shape as the cross-sectional shape of said pockets and

said pockets and openings being adapted to receive the blades of the cutting elements to be sharpened.

3. A device for holding a scissors while 70 same is being sharpened comprising a member having spaced end walls one of which is provided with a notch to receive the scissors blade which is to be sharpened, and an element associated with said member and provided with an inclined face against which a portion of the other blade of the scissors is moved to cause the first mentioned blade of said scissors to be rotated slightly within said notch whereby said blade is wedged 75 between walls of said notch and the scissors 80 is rigidly gripped by the holding device.

4. A device for holding a scissors while 85 same is being sharpened comprising a member having spaced end walls one of which is provided with a notch to receive the scissors 90 blade which is to be sharpened, and an element associated with said member provided with an inclined face having teeth against which a portion of the other blade of the scissors is moved to cause the first 95 mentioned blade of said scissors to be rotated slightly within said notch whereby said blade is wedged between walls of said notch and the scissors is firmly gripped by the holding device.

5. A device for holding a scissors while 100 same is being sharpened comprising a member having spaced end walls one of which is provided with a notch to receive the scissors 105 blade which is to be sharpened, teeth formed on the opposite end wall, and an element associated with said member and provided with an inclined face having teeth against which a portion of the other blade of the scissors is moved to cause the first 110 mentioned blade of said scissors to be rotated slightly within said notch whereby said blade is wedged between walls of said notch and the scissors is firmly gripped by the holding device.

6. A device for holding a scissors while 115 same is being sharpened comprising a member having spaced end walls one of which is provided with a notch to receive the scissors 120 blade which is to be sharpened, shoulders formed on a wall of said notch with which the scissors blade may contact, teeth formed on the opposite end wall, and an element associated with said member provided with an inclined face having teeth against which a portion of the other blade of the scissors is moved to cause the first mentioned blade of said scissors to be rotated slightly within said notch whereby said blade is wedged 125 between walls of said notch and the scissors is firmly gripped by the holding device.

7. A device for holding cutting elements while the blades thereof are being sharpened, comprising a member having spaced 130 end walls, one of which is provided with a

notch to receive a blade of a scissors which is to be sharpened, and an element associated with said member and provided with an inclined face against which a portion of the other blade of the scissors is moved to cause the first mentioned blade of said scissors to be rotated slightly within said notch, whereby said blade is wedged between walls of said notch and the scissors

is firmly gripped by the holding device, 10 said spaced walls of said member being provided with inclined open-end slots adapted to receive blades of knives when said blades are being sharpened.

In testimony whereof, I have hereunto set my hand.

WILLIAM T. BRADLEY.
